UNITED STATES PATENT OFFICE.

OTTO KONIGSLOW, OF CLEVELAND, OHIO, ASSIGNOR TO THE OTTO KONIGSLOW MANUFACTURING COMPANY, OF CLEVELAND, OHIO, A CORPORATION OF OHIO.

HINGE.

1,317,196.

Specification of Letters Patent. Patented Sept. 30, 1919.

Application filed February 23, 1915. Serial No. 9,961.

To all whom it may concern:

Be it known that I, Otto Konigsow, a citizen of the United States, residing at Cleveland, in the county of Cuyahoga and 5 State of Ohio, have invented certain new and useful Improvements in Hinges, of which the following is a specification.

This invention relates to hinges generally, and particularly to that class of such devices 10 utilized for the doors of motor vehicles.

More specifically the invention relates to a hinge comprising a frame to be permanently secured to a pillar or other portion of the body and adapted to receive and re- 15 movably hold portions of hinges secured to the door, the door portion of the hinges being preferably made integral, the entire arrangement being such that the relationship between the parts is always maintained 20 while being applied and after installation.

The invention may be further briefly summarized as consisting in the construction and combination of parts hereinafter set forth in the following description, drawings 25 and claims.

Referring to the drawings, Figure 1 is a side elevation of a portion of the side of a vehicle showing the door, with parts broken away; Fig. 2 is a side elevation of the hinge 30 construction as it appears from the outside of the car; Fig. 3 is an enlarged view looking at the hinge frame in elevation with the door member swung into open position; Fig. 4 is a section upon the line 4-4 of Fig. 2, 35 with the door closed; and Fig. 5 is a similar section with the door open.

In carrying out the invention any preferred form and construction of parts may be employed, so long as they possess the 40 necessary characteristics, but I have shown one embodiment which is effective, and in such arrangement 1 represents the pillar of the frame of the body, and 2 the framework of the door, these parts being of any preferred construction, and being cut out to receive the parts of the hinge structure.

The hinge structure comprises a fixed frame facing member 4 having a hinge socket near each end formed by offsetting 50 the metal at 5 to form a hinge facing flange depression 6 and then bending the metal downward to form a hinge receiving recess or socket having side portions 7 and a bottom or connecting portion 8, the main body 55 strap being bent at 9 to form a hinge facing

flange depression 10 on the opposite side of the loop. The bottom or connecting portion 8 adjacent to each side member 7 is provided with an opening 11 for a purpose to be described, and each of the portions 5 and 9 at 60 the strap recesses is provided with a threaded opening 12 for a purpose to be described.

The hinge mechanism proper is preferably made in a unitary arrangement including a plurality of individual hinge devices each 65 comprising a socket engaging strap for engagement in one of the recesses of the hinge frame, and tongues pivoted to the socket engaging straps and preferably formed integral with a facing strip to be secured to 70 the door facing. Each socket engaging strap consists of a pair of hinge side members 13 connected by a stop web 14 at the edge. Each side member has a lug 15 at its inner end adapted to project through the 75 corresponding opening 11 in the connecting or bottom portion of the socket of the frame member 4. The free ends 16 of the side members extend in opposite directions and in substantially the same plane and are 80 adapted to engage in the recesses 6 and 10 and form facing flanges. These extending portions or facing flanges are provided with countersunk openings for receiving machine screws 17 engaging in the threaded openings 12. In this way the socket engaging strap of each hinge device is held upon the outside by the screws and on the inside by the lugs 15 against movement or displacement. The hinge side members 13 are provided with openings 18 which receive the 85 reduced ends 19 of a pin, in each hinge device 20. Engaging this pin is a sleeve 21 formed on the end of a door hinge strap or tongue 22 preferably formed integral with 90 a main door engaging facing strip 23 countersunk in the edge face of the door and held therein by screws passing through openings 24. The sleeve portion touches substantially the same vertical plane as the edge of 95 the main strap 23 and extends in parallelism with the main strap for a short distance preferably the distance from the pivot pin to the outside edge of the web 14, and is then 100 bent with a curve and merges into the door 105 engaging facing strip 23, this portion being strengthened by suitable ribs 25 struck up from the metal. In this way the door is free to swing until the straight portion of the strap 22 engages the inside of the stop 110

web 14 when further swinging movement of the door will be prevented.

When the hinge structure is made in this way there are no parts of the hinge extending outside of the meeting edges of the door and pillar and the door may be removed and replaced without varying the adjustment since the screws 17 engage in the metal frame.

10 In motor vehicles it is a well known fact that the unevennesses in the road surface and the extreme strains and stresses to which all parts of the vehicle are subjected have a tendency to spring the frame and the body in such a manner that it is almost impossible with any of the ordinary hinge structures to maintain the doors in proper alignment so that they will latch readily at all times. It is also a fact that almost every 15 user and almost every person entering or passing out of a motor vehicle feels that the door must be slammed in order to be latched. As a matter of fact many users of motor vehicles feel that it is a mark of extreme 20 familiarity with such vehicles to carelessly and sometimes recklessly slam the door with great force. These extreme tests to which the hinge and latch mechanism of a door are subjected require that in good grades of 25 vehicles the hinge structure should be made as rigid and strong as possible to withstand the racket. Furthermore, it is often the case that a person in getting into or out of a vehicle of this type will swing his entire 30 weight on the door and as a matter of fact one of the tests to which such hinges are subjected is for a person weighing probably two hundred pounds to sit upon the edge of the door and swing when it is open, for, 35 whether this should be done or not, the prospective customer requires that the construction should stand for almost anything which he should care to do.

It is also a fact that in the construction 40 of bodies for motor vehicles it is essential that the hinges be easily applied so that the workmen may place them with as little danger of misaligning the parts as possible. It is also a distinct advantage in the art to have 45 those portions of the hinges attached to the body removable without relying upon the wood screws and so arranged as to avoid relying upon the car structure to maintain the spacing or location of the hinge parts.

In view of the foregoing conditions and requirements the device herein shown has been devised and it has met with the unqualified approval of a large bulk of the trade.

Having described my invention, I claim:

1. A complete unitary hinge structure for doors of vehicles comprising a facing frame having a plurality of spaced hinge sockets, a facing strip, and hinge devices connecting the facing frame and the facing strip and comprising tongues carried by the latter and socket engaging straps pivoted to the tongues and removably secured in the sockets of the facing frame.

2. A complete unitary hinge structure for doors of vehicles comprising a facing frame adapted to be secured to the body and having a plurality of U-shaped spaced hinge sockets, a door facing strip adapted to be secured to the door, and hinge devices connecting the facing frame and the door facing strip and comprising tongues secured to the door facing strip, U-shaped socket engaging straps pivoted to the tongues, means for securing the socket engaging straps to the facing frame, and inter-locking connections between the socket engaging straps and the bottoms of the U-shaped sockets of the facing frame for preventing lateral displacement of one of these parts with respect to the other.

3. A complete unitary hinge structure for doors of vehicles comprising a facing frame adapted to be secured to the body and having inwardly extending U-shaped hinge sockets with openings in the base of each U-shaped socket, a door strip, and hinge devices connecting the facing frame and the door strips and comprising tongues secured to the latter, U-shaped socket engaging straps pivoted to the tongues, lugs carried by said socket engaging straps and engaging in the openings in the bottoms of the U-shaped sockets of the facing frame, and means for removably holding the socket engaging straps in the sockets of the facing frame.

In testimony whereof I affix my signature in presence of two witnesses as follows.

OTTO KONIGSLOW.
